UNITED STATES PATENT OFFICE.

CHARLES B. MORROW, OF CHICAGO, ILLINOIS, ASSIGNOR TO S. HEINEMAN & CO., OF SAME PLACE.

DESIGN FOR A WALL-PAPER STAND.

SPECIFICATION forming part of Design No. 34,227, dated March 12, 1901.

Application filed January 18, 1901. Serial No. 43,819. Term of patent 3½ years.

To all whom it may concern:

Be it known that I, CHARLES B. MORROW, a citizen of the United States, residing at Chicago, in the county of Cook and State of Illinois, have invented and produced a certain new and original Design for a Wall-Paper Stand, (Case No. 1,) of which the following is a full, clear, concise, and exact description, reference being had to the accompanying drawings, forming a part of this specification.

The object of my invention is to provide a design for a stand for wall-paper.

In the accompanying drawings, Figure 1 is a view in elevation of a wall-paper stand embodying my new design. Fig. 2 is an end elevation of a portion of the same.

The stand shown in the drawings consists of a base A, having four legs a a, a pedestal B, extending upwardly from the base A, and a holder C for the wall-paper, supported by 20 the pedestal B.

The pedestal B consists of a tube, and the holder C is provided with a spindle c, which extends downwardly from the holder C.

The holder C consists of a long U-shaped 25 trough adapted to contain a number of rolls of wall-paper. The sides of the trough-shaped holder consist of an open pattern c'.

What I claim as my invention is—

The design for a wall-paper stand, substantially as shown and described.

In witness whereof I hereunto subscribe my name this 16th day of January, A. D. 1901.

CHARLES B. MORROW.
